AUTOMOBILE DISK WHEEL

Paul D. Fadow, Warren, and Erwin B. Kolt, Birmingham,
Mich., assignors to The Budd Company, Philadelphia,
Pa., a corporation of Pennsylvania

Filed Aug. 22, 1962, Ser. No. 71,408

Term of patent 14 years

(Cl. D14—30)

Fig. 1

Fig. 4

Fig. 2

Fig. 3

FIG. 1 is a perspective view of an automobile disk wheel embodying the new design;

FIG. 2 is an offset section taken at the studs and between the studs of the wheel of FIG. 1;

FIG. 3 is an enlarged partial elevation of the recessed stud area of the disk wheel;

FIG. 4 is a section taken at lines 4—4 of FIG. 3.

The essential features of the design reside in the portions shown in full lines in the drawing.

We claim:

The ornamental design for an automobile disk wheel, substantially as shown and described.
